UNITED STATES PATENT OFFICE.

JOHN HENRY ROSE, OF SHREVEPORT, LOUISIANA.

SHUTTER-WORKER.

SPECIFICATION forming part of Letters Patent No. 725,144, dated April 14, 1903.

Application filed June 13, 1902. Serial No. 111,499. (No model.)

To all whom it may concern:

Be it known that I, JOHN HENRY ROSE, a citizen of the United States, and a resident of Shreveport, in the parish of Caddo and State 5 of Louisiana, have made certain new and useful Improvements in Shutter-Workers, of which the following is a specification.

My invention is an improvement in that class of shutter-workers which are adapted 10 to be operated from the inside of a building.

It is the object of my invention to provide a simpler, cheaper, and more easily applied apparatus than those of its class heretofore employed. To this end I have adopted the construction, arrangement, and combination of 15 parts hereinafter described, reference being had to accompanying drawings, in which—

Figure 1 is a perspective view illustrating the application of my invention to a window-frame shutter or blind. Fig. 2 is a vertical cross-section taken adjacent to the operating-rod of the shutter-worker. Fig. 3 is a horizontal section. Fig. 4 is a perspective view illustrating a modification of the joint 25 between the operating-rod and the slidable rod forming an attachment of the shutter or blind proper.

The main parts of my improved shutter-worker are a jointed or two-part operating-rod A and a slidable rod B, the two being 30 pivotally connected at 1. The said slidable rod B is arranged in keepers or guides 2 in horizontal position on the inner side of the lower portion of a shutter or blind C. The 35 said guides may consist of screw-eyes, as shown. On the outer end of the rod a nut 3 is applied to serve as a stop.

The operating-rod A consists of an outer flattened portion 4 and an inner portion 5, 40 provided with a handle or knob 6. The said rod slides through a portion of the sill D of the window-frame and is also held in two keepers or guides 7 and 8. The outer guide 7 is a right-angular plate, which is screwed 45 to the inner side of the window-sill. A clamp-screw 9 passes through the horizontal flange of the guide-plate, and by contact with the slidable rod A it serves to lock the same when the shutter C is either open or closed. 50 The outer keeper 8 incloses the flattened portion 4 of the operating-rod and is made of about twice the length of the width of the

rod, so that the latter has a certain degree of lateral play therein, as may be required to accommodate the movement of the slidable 55 rod B and the shutter in opening and closing. A wear-plate 10 is secured to the inner side of the blind at a point opposite the joint 1 of the two rods A and B.

The purpose of making the outer portion 4 60 of the operating-rod A flat or rectangular, as shown, is to prevent its rotation on its axis, so that in opening and closing the shutter C no twist will occur at 1, and hence the parts will operate with minimum friction. For 65 the same purpose—to wit, to prevent rotation of the operating-rod—I may form the joint in the manner shown in Fig. 4, where the ends of the rods A and B are shown flattened and pivoted together.

In order to open the shutter C, the inner jointed end 5 of the operating-rod A is raised to horizontal position, so that it is in alignment with the inner or flattened portion 4, and the same is then pushed lengthwise inward, whereby the shutter is swung around on its hinge into the position shown in Fig. 3. The rod A is then clamped by means of the screw 9, so that the shutter is held locked in position. Contrariwise, in order to close 80 the shutter C the rod A is pulled, whereby leverage is applied to the shutter through the medium of the slidable rod B and the shutter thereby brought into the position shown in Figs. 1 and 2, when the same is locked by 85 means of the clamp-screw 9.

It will be seen that the apparatus is very easily operated for opening or closing the shutter C and that it consists of few parts, which are not liable to get out of order; further, that the apparatus may be easily applied to window-frames and shutters by boring through the window-sill and then applying the several parts in the position shown.

Having thus described my invention, what 95 I claim as new, and desire to secure by Letters Patent, is—

1. The combination with a window-frame and hinged shutter, of a slidable rod arranged horizontally in keepers on the lower 100 portion of the shutter and provided with a stop at its outer end, an operating-rod pivoted to the inner end of such slidable rod and having its outer portion constructed rectan-

gular and arranged at right angles to the slide-
able rod, and guides for the operating-rod,
one of the guides being of greater length than
the width of the rod, as shown and described.

5. 2. The combination with a window-frame
and hinged shutter, of an operating-rod slid-
ing in guides on the window-sill, and a slid-
able rod which is jointed thereto, screw-eyes
attached to the blind and serving as guides
10 for said slideable rod, and a stop on the outer
end of the latter which is adapted to engage
the outer screw-eye, substantially as shown
and described.

15 3. The improved shutter-worker, compris-
ing a slideable rod and having a stop at its
outer end, screw-eyes serving as guides for
said rod, an operating-rod which is pivotally
connected with the slideable rod, and two
20 keepers for the latter, one of which is a right-
angular plate having a clamp-screw, as shown
and described.

4. A shutter-worker comprising a rod hav-

ing a limited longitudinal sliding movement
in connection with the shutter and held in
all positions approximately parallel with the 25
plane of the shutter, and an operating-rod
jointed to the slideable rod and having a lon-
gitudinal movement in a direction trans-
versely to the direction of length of the sill
substantially as set forth.

30 5. The combination of the blind, the sill,
the rod held to the blind and having a limited
longitudinal movement in guides provided on
the blind and held in all positions approxi-
mately parallel with the plane of the blind, 35
the sill, and the operating-rod movable lon-
gitudinally in a direction transverse to the
direction of the length of the sill and jointed
at its outer end to the rod sliding on the blind
substantially as set forth.

JOHN HENRY ROSE.
